ELECTRICAL CONNECTER

Claude W. Putnam, Green Bay, Wis.

Application March 12, 1934, Serial No. 715,119

1 Claim. (Cl. 173—324)

This invention appertains to electricity, and more particularly to electrical connectors, such as plugs, sockets, line couplings, and the like.

One of the primary objects of my invention is to provide a novel electrical connector, either of the plug, socket, or line coupling type, having a swivel connection therein, whereby free turning of the wires is permitted so as to prevent the twisting and entangling thereof.

10 Another object of my invention is to provide an electrical connector including the usual body, or casing, in which is freely rotatable a supporting sleeve carrying the terminals of the line wires, with novel means for forming an electrical connection between the terminals and the terminals to be connected therewith during the rotation of the supporting sleeve.

15 A further important object of my invention is to provide an electrical connector embodying a casing having rigidly connected therein terminals for the lead-off wires, with a sleeve rotatably mounted in the casing in a novel manner receiving the lead-in wires, the sleeve carrying the terminals for the lead-in wires, the terminals of the lead-in and the lead-off wires being engaged in a novel manner to permit the free flow of current irrespective of the rotation of the sleeve.

20 A still further object of my invention is to provide a swivel coupling of the above character, which will be durable and efficient in use, one that will be simple and easy to manufacture, and one which can be placed upon the market at a reasonable cost.

25 With these and other objects in view, the invention consists in the novel construction, arrangement and formation of parts as will be hereinafter more specifically described, claimed and illustrated in the accompanying drawing, in which drawing:—

30 Figure 1 is a central, longitudinal section through an electrical connector embodying my invention, the connector being of the socket type for receiving a threaded plug, or base.

35 Figure 2 is a side elevation of an electrical connector embodying my invention, the connector being shown partly broken away and in section and of the prong plug type.

40 Figure 3 is a side elevation of an electrical connector constructed in accordance with my invention, the connector being shown partly broken away and in section and of the line coupling type.

45 Referring to the drawing in detail wherein similar reference characters designate corresponding parts throughout the several views, the letter A generally indicates one form of my improved elec-

trical connector. The connector A embodies a housing, or casing, 5 formed of insulating material, and this casing is preferably formed from inner and outer sections 6 and 7 to permit the assembling of the various parts of the connector.

5 The sections 6 and 7 of the casing, or housing, can be detachably connected together in any desired way, such as by the use of bolts 8.

Extending through the sections 6 and 7 is a longitudinally extending axial bore 9, and the section 6 is provided with a cavity 10 which opens out the outer face thereof and an inner chamber 11.

10 Suitably anchored within the cavity 10 is a metallic conductor shell 12 into which is adapted 15 to be threaded an electrical connector plug (not shown), the wires of which may lead to any preferred type of electrical appliance.

15 Rotatably mounted within the bore 9 is an axially disposed, rotatable sleeve 13, and this 20 sleeve 13 is formed from fibre, or any other preferred kind of electrical insulating material. If desired, the outer end of the bore 9 of the section 7 can be provided with a bearing ferrule 14 for the sleeve 13. As shown in Figure 1, the sleeve 25 13 extends entirely through the inner chamber 11 and terminates slightly short of the cavity 10.

20 Anchored to the sleeve 13 for rotation therewith is a bearing sleeve 15 carrying a bearing head 16. The bearing sleeve 15 and the head 16 are formed 30 of electrical conducting material, and the head 16 is preferably of an annular cup shape, which is disposed in facing relation to a similar annular conductor head 17.

25 This conductor head 17 is anchored in the 35 chamber 11, such as by the use of screws 18 which can also be employed for holding the shell 12 in place. These screws 18 also constitute means for electrically connecting the shell 12 with the conductor head 17.

30 In order to permit free rotation of the head 16 relative to the head 17 and still insure the proper flow of current between the two, an expansion coil spring 19 is placed about the insulating sleeve 13 between the heads 16 and 17.

35 The rotatable insulating sleeve 13 receives the electrical line wires 20 and 21. The wire 20 is electrically connected to the bearing sleeve 15 through the medium of a fastening screw 22. This screw 22 extends through the bearing sleeve 50 15, the rotatable insulating sleeve 13, and into a terminal head carried by said wire 20.

40 Firmly anchored in the sleeve 13 is a central bearing contact 23. This bearing contact 23 closes the inner end of the sleeve 13 and pref-

erably, but not necessarily, carries the spring-pressed contact plunger 24. A screw 25 can be employed for holding the central contact to the rotatable sleeve.

5 The end of wire 21 is rigidly connected to the central contact and can be soldered thereto, if desired.

In use of my improved connector, the electric plug is threaded into the shell 12, and the shell 10 plug engages the shell 12 of the socket and the center contact of the plug engages the contact plunger 24.

Should any twisting movement occur in the wires, the casing 5 can freely rotate on the sleeve 13, or the sleeve 13 can freely rotate within the casing.

Due to the fact that the wires 20 and 21 are carried by the sleeve 13, the twisting and entangling of the wires is prevented during rotation 20 of the sleeve 13 relative to the casing. The bearing head 16 rotates relative to the conductor head 17, but the transmission of the current is insured in view of the coupling spring 19. The plunger 24 merely turns on the central contact of the plug.

25 In Figure 2, I have shown an electrical plug of the prong type, and this plug is constructed in the same manner as that form of my invention shown in Figure 1. Hence, the plug embodies the casing 30 formed of insulating material rotatably receiving the fibre sleeve 31 to which is anchored the lead-in wires, and these wires are electrically connected respectively to the central contact head 23 and the bearing head 16.

Instead of providing the shell 12, I provide 35 the conductor prongs 32 and 33. These prongs are held in place respectively by screws 34 and 35. The screw 34 likewise holds the conductor head 17 in place and forms an electrical connection between the prong 32 and the head 17. The prong 33 is provided with a base 36 which engages 40 the central contact head 23.

The function of the plug shown in Figure 2 is identical with the function of the socket shown in Figure 1.

45 In Figure 3 of the drawing, I have shown my invention embodied in an electrical line coupling

40. The coupling 40 is identical with those forms of my invention shown in Figures 1 and 2, the only difference being that the casing 41 of the coupling is provided with binding posts 42 and 43 for receiving the terminals of the outgoing 5 wires 44 and 45.

The post 42 is electrically connected with the conductor head 17, and the post 43 is provided with a base 46 for electrically engaging the central contact head 23. In this form the insulating 10 sleeve 13 is freely rotatable, and hence twisting of the wires is prevented.

From the foregoing description, it can be seen that I have provided a novel means for connecting electrical appliances with outlets and the like 15 without twisting and breaking of the wires irrespective of the twisting movement of the wires incident to the use of the electrical appliances.

Changes in details may be made without departing from the spirit or the scope of the invention, but what I claim as new is: —

A swivel electrical connector comprising a casing 25 embodying longitudinally aligned, substantially cylindrical sections having adjacent ends abutting, means detachably connecting the sections 30 together, one of said sections having an inner chamber and both of said sections having aligned, axial bores communicating with the chamber, an insulating sleeve freely rotatable in the bores, an annular conductor head secured to the exterior 35 of the sleeve for rotation therewith and disposed in said chamber, an annular conductor head disposed in the chamber around the sleeve and anchored to the walls of the chamber, an electrical 40 conducting coil spring interposed between said heads, a side contact electrically connected with the head carried by the walls of the chamber, an axially disposed central contact rigidly secured to the sleeve and rotatable therewith and extending exteriorly of the bore in spaced relation to the side contact, line wires extending into the insulating sleeve, and means electrically and rigidly connecting the wires to the central contact and to the annular conductor head carried by the sleeve.

CLAUDE W. PUTNAM.
